UNITED STATES PATENT OFFICE.

HINOSUKE ARIKA, OF TOKYO, JAPAN.

MECHANISM FOR AUTOMATICALLY REPLENISHING WEFT IN POWER LOOMS.

Application filed April 14, 1925, Serial No. 22,989, and in Japan April 24, 1924.

This invention relates to automatic weft replenishment in power looms, consisting in a board that slides up and down in back of a shuttle box, opening or closing such box as required by its sliding motion upward or downward; a push rod which ejects useless shuttles out of the box; a reserve-shuttle depository; and a shuttle-carrier, all so arranged that whenever a weft-thread breaks, or a shuttle is used up or thrown out of the box a new shuttle will be automatically inserted in the lay. Motion is transmitted from the main shaft to a change shaft the sliding board of the shuttle box moved upward, the push rod ejects the shuttle, after which the shuttle carrier receives a shuttle from the depository and carries it to the shuttle box, the sliding board then coming half way down and supporting the shuttle. The shuttle carrier then moves away, the sliding board closes the shuttle box, and the work of weaving is resumed. The object of this invention is to increase efficiency of weaving by automatically replenishing the weft when it is broken, or the shuttle is used up or thrown out of the box and to continue the work of weaving.

The accompanying figures show my invention in which

 Fig. 13 is a plan view of the push rod mechanism.
 Fig. 14 is a side view of a reserve shuttle depository and shuttle box, and mechanism

for carrying a shuttle from the former to the latter.

Fig. 15 is a sectional side view of the shuttle box showing how a shuttle is ejected. 60

Fig. 16 is a view similar to Fig. 15, showing the shuttle box when a new shuttle is fed in.

Fig. 17 is a view also similar to Fig. 15, showing the shuttle box when a new shuttle 65 has been fed in and the carrier retired.

Fig. 18 is a side view of cam-mechanism which actuates the push rod.

Fig. 19 is a side view of cam-mechanism which actuates the sliding board of the shuttle box. 70

Fig. 20 is a side view of the cam-mechanism which actuates the shuttle carrier.

In Figs. 1 and 2, (1) is a main or crank shaft, (25) is a change shaft and (60) is a 75 reserve-shuttle depository. Normally the change shaft (25) does not rotate, but when it becomes necessary to change the shuttle, it begins to rotate and by means of cams provided on the same shaft the motion is transmitted to the shuttle box (90), the shuttle contained therein being thrown out of the box and out of the loom through a funnel (78) and one of the reserve shuttles in the depository is delivered to the box. 80 The mechanism for performing this change is described hereinafter. 85

I will first describe transmission of power from the crank shaft (1) to the change-shaft (25). 90

To the crank shaft (1) as shown in Figs. 1 and 9, is fixed a friction disc (2) which also serves as a fly wheel. Loosely mounted on the shaft (1) is a disc (3) which is to engage the disc (2) and a belt pulley (5), rigidly connected with the disc 3. A loose belt pulley (6) is also loosely fitted on the said shaft. A clutch shifter (18), which is to move the clutch disc (3), is connected with a crank lever (16) by a link (17). Another crank lever (15), which is firmly fixed to the same shaft, is connected at (9) with a handle (8), which is fulcrumed at (7), by means of a link (13), a bell crank (12) and another link (10). Thus if the handle (8) is shifted to the left in Fig. 8, the clutch disc (3) firmly engages the clutch disc (2), and as the belt pulley (5) is then clutched to the crank shaft (1), the work of weaving commences. A rocking shaft 20 supports a lay (38), on which are mounted, as shown in Figs. 1 and 2, a chain wheel (21) and toothed wheel (22) firmly con- 100
 105
 110

nected with each other, the chain wheel (21) being connected by means of a chain (19) with the sprocket (4) firmly fixed to the belt pulley (5). The change shaft (25) is mounted on a frame (37), (39) and (40) which is firmly fixed to the lay (38), and to this shaft is loosely mounted a toothed wheel (26) which is rotated by a toothed wheel (22) on a shaft (20) through intermediate toothed wheels (23) and (24). To the said toothed wheel (26) is fixed a clutch member (27), and another clutch member, (28) which is to engage the clutch member 27, is fixed to the shaft (25); a forked rod (35) which is guided by shafts (20) and (36), as shown in Figs. 1 and 8, is connected to the handle (8) at its lower part (77) by a link (33), bell crank (32) and another link (30). Thus, if the handle (8) is moved toward the left in Fig. 2 and the work of weaving is resumed, the clutch members (27) and (28) disengage, but if the handle (8) is moved to the other direction, then the friction clutch members (2) and (3) of the crank shaft (1) disengage and at the same time the clutch members (27) and (28) engage. The weaving portion of the loom then becomes inoperative, but the belt pulley (5) continuing rotation, the change shaft (25) is rotated through the chain (19) and toothed wheel, such movement of the handle (8) toward the right taking place automatically when the weft breaks, or the shuttle is used up or is thrown out of the shuttle box, the handle (8) being actuated by a weft-side-fork (46) (Fig. 3), and pushed by a fork-lever (47). Such weft-side-fork and fork-lever are well known as stopping mechanism. As shown in Fig. 8, a toothed wheel (45) is firmly fixed to the shaft (25), and drives through intermediate toothed wheels a toothed wheel (75) firmly fixed to a shaft (74). To the shaft (74) a cam (76) is firmly fixed, and thus when the shaft (25) has almost finished one rotation, the cam (76) pushes the lower end of the handle (8) toward the right, the work of weaving is resumed, clutch members (27) and (28) being disengaged and the friction clutch (2) and (3) being brought to contact.

The shuttle box is constructed as shown in Figs. 11 and 12, and consists of a sliding board (50) which can slide up or down and forms the back wall of the box. Through the front wall a pushing rod (54) which is connected to one arm of a bell crank lever (53) pivoted to a bracket (52) firmly attached to the shuttle-box, passes through, and the other end of the same bell crank lever (53) is connected to a rod 51, which is, as shown in Fig. 18, is provided at its lower part with a slot. A roller (49) is mounted on the rod (51), and through the slot the change shaft (25) is passed through, so that a cam (42) firmly fixed to the change-shaft (25) is in contact with the roller (49). To the slid-

ing board (50) is connected a rod (48) which is provided at its lower part with a slot through which the change shaft (25) passes, as shown in Fig. 19. A roller (49) mounted on this rod (48) is in contact with a cam (41) which is firmly fixed to the change shaft (25). Thus when the change shaft (25) makes one rotation, the push rod (54) moves forward and backward once, and the sliding board (50) slides up and down once. The board (50) moves upward uniformly, but while descending it stops in an intermediate position remaining for a moment at the half closed position.

The reserve shuttle depository (60), as shown in Figs. 5, 6, and 7, is firmly fixed to the frame of the loom at a relative position as shown in Fig. 14 with regard to the shuttle box, and is a bottomless box with pivoted shuttle supporting-rods (63) and (65), one on the front and the other on the back. The upper bent part of these shuttle-supporting-rods entering the depository one slightly below and the other a little above the bottom. These two rods are connected with each other with a link (64), and the link (64) is connected with an arm of a bell crank lever (62). The other arm of the bell crank lever (62) is connected with one end of a flexible power-transmitting rod (91), the other end of which is connected with a lever (56) which is to be moved, as shown in Fig. 2, by a cam (45). Thus, when the shaft (25) makes one rotation, the shuttle-supporting-rods (63) and (65) make one oscillation; that is, when the shuttle-supporting-rods (63) and (65) move toward the left as shown in Fig. 7, the lowest shuttle (92) in the depository which has hitherto been supported by the shuttle-supporting-rod (63) will be dropped down, the next lowest shuttle being supported by the shuttle-supporting-rod (65); and when the shuttle-supporting-rods move in the opposite direction that shuttle will become the lowest one in the depository.

A shuttle-carrying rod (66) is loosely mounted on the shaft (20), and the upper part of this shuttle-carrying rod is bent into a shuttle-receiver (93). A lever (68) turns on the same shaft (20), and this lever (68) and the shuttle-carrying rod (66) are connected with a spring (70), the pulling action of the spring (70) being limited by an adjusting screw (71). A cam (44) is firmly fixed to the change shaft (25), and this cam (44) and a roller (67) at the upper part of the lever (68) are always in contact as the center of gravity of the combination of the shuttle-carrying rod (66) and the lever (68) lies toward the back (the left side in Fig. 14). When the cam (44) rotates and its convex part pushes the roller (67), the shuttle carrying rod (66) moves to the right from the position shown in Fig. 14, and the shuttle-receiver (93) at the upper part enters

the shuttle-box as shown in Fig. 16. The shuttle carrying rod (66) being pulled toward the lever (68) by the spring (70) but restricted by the adjusting screw (71), the shuttle-receiver will stop when it has entered the shuttle-box, although the lever (68) still receives motion, and when the shuttle-carrying rod (66) retires, it will stop just below the shuttle-depository by the adjusting action of the adjusting screw (71).

In this invention, if after the commencement of the work of weaving by moving the handle (8) toward the left in Fig. 2, the weft breaks, or the shuttle is used up or thrown out of the shuttle-box, the weaving portion of the loom stops and the change-shaft (25) begins to rotate. As shown in Fig. 15, the cam (41) through the rod (48) pushes the sliding board (50) upward thus opening the back of the shuttle box; and then the recessed part of the cam (42) causes the rod (51) to descend, and the push rod (54) advances forward, ejecting the shuttle which leaves the loom through the funnel (78). During this time, a new shuttle lying at the lowest position of the reserve-shuttle depository, drops down on the shuttle receiver of the shuttle-carrying-rod (66), as shown in Fig. 7, by action of the cam (43). The shuttle-carrying-rod (66) then moves forward (toward the right in Fig. 14) by action of the cam (44) and carries the shuttle thereon to the shuttle box as shown in Fig. 16. At this time, the sliding board (50), actuated by the medium projection of the cam (41), descends to the half closing position, as shown in Fig. 17, and holds the shuttle, the shuttle-carrying rod (66) retires, leaving the shuttle in the shuttle box. Then the sliding board (50) descends to the lowest position, being actuated by the lowest part of the cam (41), and maintains the shuttle in the working position. At this time the cam (76) of the shaft (74) pushes the handle (8) back to its former position, the change-shaft stops its rotation, and the work of weaving is resumed.

In this invention, any shuttle that becomes unusable, is thrown backward from the shuttle-box, and a new shuttle is supplied from the reserve-shuttle-depository on the back of the shuttle-box, all automatically; and not only the weft is supplied most accurately, but many new shuttles being kept in the depository which are supplied in turn as the occasion requires, one workman can have many looms under his charge, and as it is very simple in construction, it can be fitted to any loom.

Claims:

1. Mechanism for automatically replenishing the weft in a power loom, comprising, in combination, a main shaft, a driving pulley loosely mounted and slidable with a friction disc on the main shaft, a second friction disc fixed to the main shaft, a change-shaft, a clutch on the change-shaft, a handle, links and levers connecting the handle with the aforesaid slidable pulley and disc on the main shaft, a clutch shifter connected to said handle for shifting one of the members of the aforesaid clutch of the change-shaft, means for transmitting motion from the driving pulley to the change-shaft through the clutch, means for moving the handle whenever the weft breaks or is missing to free the slidable disc to stop the weaving operation and let in the aforesaid clutch member to effect a change of shuttle, a cam rotatable from the change-shaft to reset the handle and restart the weaving operation, a shuttle box provided with a slidable board arranged to open and close the back of the box, a push rod adapted to move through the front wall of the box and push backward the shuttle in the box, cams on the change-shaft to actuate said slidable board and push rod, a reserve shuttle magazine, a shuttle transerrer and means on the change-shaft for moving the transerrer to carry a fresh shuttle from the magazine into the shuttle box upon the shuttle in the latter being ejected by means of the push rod.

2. Mechanism for automatically replenishing the weft in a power loom, according to claim 1, wherein the slidable board of the shuttle box is moved up and down to open and close the box by means of a rod having a roller in contact with the board operating cam on the change-shaft, said cam being so shaped that the board during its downward or closing movement is momentarily retained in a partly closed position so as to hold the newly inserted shuttle in the box while the shuttle transerrer recedes.

3. Mechanism for automatically replenishing the weft in a power loom, according to claim 1, wherein the shuttle transerrer is pivoted on a shaft on which an actuating lever for said transerrer is also pivoted, said transerrer and lever being drawn towards one another by a spring, and adjustable means being provided for limiting their relative positions.

In testimony whereof I have affixed my signature.

HIKOSUKE ARIMA.
